(57) **CLAIM**

I claim the ornamental design for a first aid product supply container, as shown and described.

DESCRIPTION

FIG. 1 is a front, right, perspective view showing my design of a first aid product supply container;

FIG. 2 is a back elevation view thereof;

FIG. 3 is a top plan view thereof;

FIG. 4 is a bottom plan view thereof;

FIG. 5 is a left side elevation view thereof;

FIG. 6 is a front elevation view thereof; and,

FIG. 7 is a right side elevation view thereof.

The broken lines showing tabs extending from the container, and an upper panel on the front surface are for illustrative purpose only and form no part of the claimed design.
